[57] CLAIM

I claim the ornamental design for a vent cover, as shown and described.

DESCRIPTION

FIG. 1 is a perspective view of one embodiment of a vent cover in accordance with the present invention.

FIG. 2 is a side elevation view of the vent cover of FIG. 1, it being understood that the vent cover has the same appearance from all sides.

FIG. 3 is a front view of the vent cover of FIG. 1.

FIG. 4 is a back view of the vent cover of FIG. 1.

FIG. 5 is a cross-sectional view of the vent cover of FIG. 1, taken along line 5—5 of FIG. 3.

FIG. 6 is a perspective view of a second embodiment of a vent cover in accordance with the present invention.

FIG. 7 is a side elevation view of the vent cover of FIG. 6, it being understood that the vent cover has the same appearance from all sides.

FIG. 8 is a front view of the vent cover of FIG. 6.

FIG. 9 is a back view of the vent cover of FIG. 6; and, FIG. 10 is a cross sectional view taken on line 10—10 of FIG. 8.
